United States Patent Office

Des. 196,273
Patented Sept. 10, 1963

196,273

GASOLINE CAN

Edward J. Suess, Chicago, Ill., assignor to Edward Can
Company, Chicago, Ill., a corporation of Illinois

Filed Jan. 7, 1963, Ser. No. 73,076

Term of patent 14 years

(Cl. D58—17)

FIG. 1

FIG. 2

FIG. 3

FIG. 4

FIG. 5

FIGURE 1 is a top plan view of a gasoline can showing my new design.

FIG. 2 is a side view of the same.

FIG. 3 is a bottom view of the same.

FIG. 4 is a front end view of the same; and

FIG. 5 is a rear end view of the same.

The side not shown is a mirror image of the side shown in FIG. 2.

I claim:

The ornamental design for a gasoline can, as shown and described.
